UNITED STATES PATENT OFFICE.

ERNEST R. PHILIP, OF ATLANTA, GEORGIA, ASSIGNOR TO AMERICAN CAN COMPANY, OF NEW YORK, N. Y., A CORPORATION OF NEW JERSEY.

SHEET-METAL SAP-COLLECTING APRON AND RECEPTACLE.

No. 858,305.

Specification of Letters Patent.

Patented June 25, 1907.

Application filed March 14, 1907. Serial No. 362,291.

To all whom it may concern:

Be it known that I, ERNEST R. PHILIP, a citizen of the United States, residing in Atlanta, in the county of Fulton and State of Georgia, have invented a new and useful Improvement in Sheet-Metal Sap-Collecting Aprons and Receptacles, of which the following is a specification.

My invention relates to improvements in sheet metal sap collecting aprons and receptacles.

The object of my invention is to provide a sheet metal sap collecting apron and receptacle of a strong, simple, efficient and durable construction, capable of being cheaply manufactured, and which will also serve to protect the turpentine or other sap collected in the receptacle from deterioration in quality by reason of dirt or foreign matter falling into the receptacle.

My invention consists in the means I employ to practically accomplish this object or result as herein shown and described, and more particularly specified in the claims.

In the accompanying drawing forming a part of this specification, Figure 1 is a front elevation of a sap collecting apron and receptacle embodying my invention. Fig. 2 is a vertical cross section. Fig. 3 is a central, 30 vertical, longitudinal section of the receptacle. Fig. 4 is an end view. Fig. 5 is a section on line 5—5 of Fig. 4 and Fig. 6 is a detail plan view showing the sheet metal blank in the flat from which the receptacle is formed.

In the drawing, A represents a sap bearing tree, B the sheet metal apron inserted in the cut a of the tree, C a wire hanger for supporting the receptacle from the apron, D the receptacle and F its cover. The sheet metal 40 apron B has divergent end flanges b furnished with slots or notches b¹ therein to receive the wire hanger C of the receptacle. The wire hanger C has oppositely turned or facing hanger arms C¹, and it is preferably secured at its body portion to the receptacle D at the upper edge of its inner side.

The sheet metal receptacle D is preferably formed in one piece from a flat blank D¹ by suitable bends or folds therein, thus having 50 an integral bottom d, integral upright longitudinal sides d¹, integral flaring ends d² and integral angle folds d³ d⁴, two of the angle folds d⁴ having integral locking lips d⁵ which

are folded over the upper edges of the flaring ends d² to lock or clamp the overlapping angle folds in place. The receptacle D is furnished at its inner upright side d¹ with an integral curved upper longitudinal edge d⁶ which embraces the straight or body portion of the wire hanger C. The receptacle D is provided at the upper longitudinal edge of its outer upright side d¹ with an integral curved flange or roll d⁷ which serves to stiffen and strengthen the outer longitudinal side of the receptacle D.

The cover is preferably connected or hinged to the receptacle D at the upper longitudinal edge of its outer upright side d¹; and it is preferably thus hinged or connected by means of an integral curved flange 70 or roll f at the lower longitudinal edge of the cover F which embraces and is adapted to telescope over the curved longitudinal edge or roll d⁷ at the upper edge of the outer upright side d¹ of the receptacle D. At its inner or free edge the cover F may overlap or rest upon the lower or mouth portion of the apron B as will be readily understood from Figs. 1, 2 and 4 of the drawing. The cover F may be readily removed or disengaged from the 80 receptacle D by simply slipping the same lengthwise. The receptacles may thus be nested for shipment, as may also be the aprons B and covers F. As the cover F is hinged to the outer longitudinal upright side 85 of the receptacle and rested at its inner portion upon the apron B, it is given the requisite pitch or inclination to properly deflect rain, dirt or other foreign materials which would otherwise fall into the receptacle.

While I prefer to apply the removable cover F to the outer longitudinal side of the receptacle, it will be understood by those skilled in the art that the cover may, if desired, be otherwise applied.

The lower portion or mouth of the apron B fits between and under the oppositely turned hanger arms C C¹ and over the inner upper edge of the receptacle D and under the inner edge of the cover F. If desired, the 100 cover F may be removed from the receptacle D before the receptacle is removed from the apron B, but as the cover fits loosely on top of the apron, the receptacle may be removed from the apron without removing the cover 105 from the receptacle.

I claim:—

1. In a sheet metal sap receiving apron and receptacle, the combination with an apron having divergent end flanges furnished with hanger receiving slots, of a receptacle having an integral bottom, upright sides and flaring ends and angle folds, and furnished at the upper longitudinal edge of its inner side with a roll, a wire hanger embraced by said roll and having oppositely turned hanger arms embracing the lower or mouth portion of the apron and fitting in the slots of the apron end flanges, said receptacle having a roll at the upper longitudinal edge of its outer side, and a cover overlapping at its upper edge the apron, and having a roll at its lower longitudinal edge telescoped with and embracing said roll at the upper edge of the outer side of the receptacle, substantially as specified.
2. The combination with a sap collecting apron, of a receptacle supported thereby and a detachable cover for the removable receptacle overlapping the lower portion of the apron, substantially as specified.
3. The combination with a sap collecting apron, of a receptacle supported by the apron and fitting at its inner upper edge under the apron and a cover hinged to the upper edge of the outer side of the receptacle and overlapping the lower portion of the apron, substantially as specified.
4. The combination with a sap collecting apron having divergent end flanges, a receptacle, means for removably supporting the receptacle from the apron and a removable cover overlapping the lower end of the apron, substantially as specified.

5. The combination with a sap collecting apron having divergent end flanges, a receptacle, means for removably supporting the receptacle from the apron and a cover, said cover being removably connected to the receptacle and overlapping the lower end of the apron, substantially as specified. 40

6. The combination with a sap collecting apron and a removable sap receptacle having a roll at its upper edge, of a removable cover having a roll telescoped with the roll on the receptacle, substantially as specified. 50

7. The combination with a sap collecting apron and a removable one piece sheet metal sap receptacle having an integral bottom, upright sides, ends and angle folds, and provided at the upper longitudinal edge of its outer side with an integral curved flange and a removable cover having at its lower edge a curved flange telescoped with said curved flange on the receptacle, substantially as specified. 55

8. The combination with a one piece sheet metal sap receptacle having an integral bottom, upright sides, ends and angle folds, and provided at the upper longitudinal edge of its outer side with an integral curved flange and a cover having at its lower edge a curved flange telescoped with said curved flange on the receptacle, said receptacle having at the upper longitudinal edge of its inner side a curved flange and a wire hanger embraced thereby, substantially as specified. 65 70
